UNITED STATES PATENT OFFICE.

FRANÇOIS LOUVRIER, OF PAIMBOEUF, FRANCE.

ELECTROMETALLURGICAL FURNACE.

1,342,636.

Specification of Letters Patent.

Patented June 8, 1920.

Application filed April 5, 1919. Serial No. 287,795.

To all whom it may concern:

Be it known that I, FRANÇOIS LOUVRIER, a citizen of the French Republic, residing at Paimboeuf, Loire Inférieure, France, have 5 invented certain new and useful Improvements in Electrometallurgical Furnaces; and I do hereby declare that the following is a full, clear, and exact description of the invention, such as will enable others skilled in 10 the art to which it appertains to make and use the same.

The present invention relates to electro-metallurgical furnaces and more particularly to such furnaces especially adapted for 15 the reduction of zinc ore and of metallic ores which are volatile at their rising temperatures. Herebefore many experiments have been made with electric furnaces for producing industrial zinc but these furnaces have 20 not given the results desired.

An object of the present invention is to provide an electro-metallurgical furnace wherein the temperature is kept uniform in the zone of reduction, the ores to be treated 25 will enter this zone in a perfectly dry state and the atmosphere being entirely excluded from the zone of reduction whereby the electrothermic production of zinc will be commercialized.

With the above and other objects in view which will hereinafter appear as the description continues, the invention consists of the novel features of construction, combination and formation of parts as will be herein- 35 after more fully described and particularly pointed out in the appended claims.

In the accompanying drawings has been shown a simple and preferred form of the invention, it being, however, understood that 40 no limitation is necessarily made to the precise structural details herein exhibited, but the right is hereby reserved to any changes, alterations or modifications to which recourse may be had that come within the 45 scope of the claims without departing from the spirit of the invention or sacrificing the efficiency of the same.

In the accompanying drawings:

Figure 1 is a vertical section through the 50 furnace embodying the present invention;

Fig. 2 is a horizontal section taken on the line 2—2 of Fig. 1;

Fig. 3 is an enlarged detail section through the furnace;

Fig. 4 is a horizontal section through Fig. 5; and,

Fig. 5 is a detail section of a slightly modified means for supporting the vertical electrodes.

Referring now more particularly to the 60 accompanying drawings wherein like and corresponding parts are designated by similar reference characters throughout the several views.

The furnace as a whole comprises a body 65 portion 1 having a reduction chamber 2 adapted to receive the zinc ores which are supplied through the feeding column 3. The walls of the furnace are formed of refractory material not susceptible of entering 70 into the reaction with the treated metal or slags. The body portion of the furnace is preferably cylindrical and arranged upon the center of the bottom of the furnace is a central pedestal or sleeper 4 having its upper face tapered so as to converge toward 75 the bottom of the furnace, and arranged around this pedestal is a trench 5 forming an annular crucible. Communicating with this crucible are outlet openings which have 80 leading therefrom the spouts, one of which indicated by the numeral 6 is for the slag and the other one indicated by the numeral 7 is for drawing off the metals, and it will be noted that these spouts are arranged at 85 different levels and the last a little above the bottom of the crucible so that a thin layer of metal may at all times rest within the base of the crucible. The pedestal 4 may have one or more electrodes indicated by the 90 numeral 8 and arranged within the bottom of the crucible are the electrodes 9 which are in permanent contact with the layer of metal within the bottom of the crucible. These electrodes 8 and 9 can be connected by a suitable conductor 10.

The roof 11 of the furnace has depending therethrough a plurality of electrodes 12 being preferably six in number and are arranged in a circle above the crucible 5. These electrodes may be raised 95 and lowered by any suitable mechanical means and are supported within air-tight stuffing boxes 13. The feeding column comprises a pair of spaced walls 14 which form an annular chamber 15 therebetween and 100 the adjacent peripheries of these walls 14 are provided with a plurality of shelves 16. Encircling the upper end of the feeding column is a carbon supply chamber 17 which is adapted to communicate with the chamber 110 15 through the valve controlled openings 18. From this, it is apparent that this coal

dust arranged within the chamber 17 will pass down through the chamber 15 and finally into the furnace, but the coal dust when passing through the chambers will be retarded by the shelves 16 which are arranged in staggered relation.

Communicating with the upper end of the chamber 15 is an outlet pipe 19 which leads the zinc vapors to suitable condensers. The 10 stuffing boxes 18 are made of suitable insulating material, and comprise a casing 20 which forms a receptacle for holding the coal dust and arranged within the bottom of this receptacle is a valve 21. These valves 15 are adapted to be manually oscillated through the handle 22 and their bottoms are provided with perforations 23 which are adapted to register with other perforations made into a flat and fixed piece 23 so that 20 the coal dust may enter into the zone of reduction around the electrodes.

The zinc ore is fed into the chamber through the feeding column and will finally be deposited within the reduction chamber 25. 2. The electrical disposition and the tension employed may differ according to the dimensions and the nature of the current utilized; the distance between the electrodes 12 and the central electrodes 8 may be regulated, so 30 that they will obviously be proportioned to the tension existing between themselves. In any case the current will be distributed in such a way that it will traverse the largest possible proportion of the ores to be treated 35 with an intensity as uniform as possible.

By this arrangement of the electrodes it is obvious that the layer of metal within the crucible and the central electrode 8 constitute the neutral points. Resulting that the 40 mass to be treated which accumulates within the reduction chamber is traversed on all of its sides by the electric current and thus brought to a uniform temperature throughout. This temperature may be modified according to the requirements by varying the 45 suspension of the movable electrodes 12. By stuffing boxes an absolute electric seal is established for excluding the atmospheric air.

By introducing coal dust into the reduction 50 chamber around the electrodes, the consumption of these is reduced, the reduction of the ores is facilitated and the existence of carbonic acid inside of the furnace is prevented. By providing the annular chamber around 55 the feeding column, the ores before they are introduced into the reduction chamber are dried and brought to a high temperature by means of the lost heat from the furnace, and as the metallic vapors pass through this 60 annular chamber they are subjected to a slow cooling process. Besides the introduction of coal dust into the annular chamber upon the shelves allows to reduce into carbon dioxid the carbonic acid which might

be produced accidentally in the reduction chamber.

Having thus fully described my invention, what I claim as new and desire to secure by Letters Patent is:

1. An electro-metallurgical furnace comprising a reduction chamber, a feeding column leading thereto, an annular chamber surrounding said feeding column and leading to said reduction chamber, and means for supplying coal dust upon shelves into 75 said annular chamber substantially as and for the purpose specified.

2. An electro-metallurgical furnace comprising a reduction chamber, a feeding column leading to said reduction chamber, said 80 feeding column comprising a pair of spaced walls forming an annular conduit therebetween, a plurality of shelves arranged between said walls in staggered relation, means whereby coal dust may be fed upon the 85 shelves, and a pipe for leading zinc vapors from the upper end of said annular conduit to suitable condensers substantially as and for the purpose specified.

3. In an electro-metallurgical furnace 90 comprising a body portion having a reduction chamber, a pedestal arranged within said body portion, a crucible encircling said pedestal, electrodes arranged within said pedestal and said crucible, and a plurality 95 of vertically adjustable electrodes depending within said reduction chamber and arranged above said crucible substantially as and for the purpose specified.

4. In an electro-metallurgical furnace 100 comprising a body portion having a reduction chamber, a crucible arranged within said body portion, a feeding column leading to said reduction chamber, a plurality of electrodes depending within said reduction 105 chamber, stuffing boxes for supporting said electrodes, said stuffing boxes adapted to retain coal dust, and valves arranged within said stuffing boxes whereby the coal dust may be delivered to said reduction chamber 110 substantially as and for the purpose specified.

5. An electro-metallurgical furnace comprising a reduction chamber, a feeding column leading to said reduction chamber, said 115 feeding column comprising a pair of spaced walls forming a condensing chamber therebetween, a plurality of shelves arranged between said walls in staggered relation, means whereby coal dust may be fed through said 120 condensing chamber into said reduction chamber and a condensing pipe leading from the upper end of said condensing chamber substantially as and for the purpose specified.

In witness whereof I have hereunto set my hand

FRANCOIS LOUVRIER.
